UNITED STATES PATENT OFFICE

JEAN B. SABOURIN, OF NORTON, MASSACHUSETTS

CIGARETTE MAKING DEVICE

Application filed November 24, 1931. Serial No. 576,959.

This invention relates to improvements in cigarette making devices.

It is an object of the invention to provide a device which can be manually operated to make cigarettes, which will approximately measure the amount of loose tobacco needed for a cigarette, and which can be conveniently carried in a pocket or hand bag. Other objects and features which characterize the invention will be appreciated as the description develops.

The accompanying drawings show the best modes in which I have contemplated applying the principles of my invention but these are merely illustrative and it is intended that the patent shall cover by suitable expression in the appended claims whatever features of patentable novelty exist in the invention disclosed.

20 In the drawings:

Figure 1 is a view of one form of my device as it would appear when not in use;

Figure 2 is a median section as on line 2-2 of Figure 1;

25 Figure 3 shows the cap-sleeve removed from the compression tube and a paper wrapper partly applied to the latter;

Figure 4 shows the cap-sleeve replaced over the paper wrapper;

30 Figure 5 shows the compression plunger and cover-sleeve withdrawn and a charge of tobacco in the loading hopper;

Figure 6 shows the relation of parts at a stage in the making of the cigarette;

35 Figure 7 shows the cap-sleeve with the finished cigarette partly ejected therefrom;

Figure 8 is a cross-section through the cap-sleeve, as on line 8-8 of Figure 6;

40 Figure 9 illustrates how the plunger end may be used in placing a prepared paper wrapper on the compression tube;

Figure 10 shows how the prepared paper wrapper may be made cylindrical;

45 Figure 11 is a median section of a modified form of loading hopper;

Figure 12 is a full view of the hopper of Figure 11;

Figure 13 shows another form of device in its inoperative condition;

50 Figures 14 and 15 are sectional views as

on lines 14-14 and 15-15 of Figure 13, showing the loading hopper in open and closed positions respectively;

Figure 16 shows the device of Figure 13 with the loading plunger withdrawn, the hopper filled with tobacco and the paper wrapper ready to be loaded;

Figure 17 is a view of still another modification of the device;

Figures 18 and 19 are views of the left end of the device seen in Figure 17, showing the plate cover closed and opened respectively; and

Figure 20 is a view of the device of Figure 17 with the loading plunger withdrawn, the hopper filled, and the paper wrapper in place.

Referring more particularly to the drawings, and especially to Figures 1 to 8, the illustrated form of the device has a compression tube 1 which is substantially of the same diameter and length as the ordinary cigarette. The wall of this tube is thin and preferably made from seamless metal tubing. It is provided with a cap-sleeve 2 which is enough larger than the tube to permit a paper wrapper 3 to be placed between them.

When the ordinary prepared sheets of cigarette paper are used, the cap sleeve is removed while the paper sheet is wrapped around the tube. In Figure 3 such a sheet is shown partly wrapped and when completely wrapped the paper is stuck to itself by the adhesive 3a provided at one edge to be moistened by the tongue. With the paper sheet thus completely wrapped on the compression tube, the cap-sleeve is slipped over the paper until an ejector plate 4 which is provided in the sleeve engages the end of the tube. This plate is positioned crosswise in the sleeve and has a pair of diametrically opposed arms 4a (see Fig. 8) which extend through longitudinal slots 2a in the sleeve and constitute finger grips. For a reason which will later be understood, the wrapper before loading begins should be positioned slightly beyond the end of the tube as shown in Figure 4. This is accomplished by pressing the sleeve against the paper—this being

easily accomplished by virtue of the slots 2a—and moving them both along the tube until a portion of the wrapper is positioned beyond the tube with its end against the 5 deflector 4.

Attached to the end of the compression tube is a hopper 5 which may likewise be made of metal or, if desired, can be of a compound material such as "Bakelite" or the 10 like. The hopper shown in Figures 1 to 12 is cylindrical and is conveniently of greater diameter than the compression tube, being internally tapered where it joins the latter. In the device shown in Figures 1 to 6 inclusive 15 the barrel has a longitudinal opening 5a in its side through which the tobacco is introduced. This opening is normally covered by a cover-sleeve 6 which as here shown slides lengthwise of the hopper, but which 20 might be arranged to rotate and have an opening adapted to register with the opening in the latter.

With the paper and cap-sleeve arranged as in Figure 4, the cover-sleeve is pulled 25 outward along the hopper until a suitable pin, such as the screw 6a, reaches the end of a groove 5b in the hopper thus limiting the degree of withdrawal. The exposed end 30 7a of a loading plunger 7 is now turned to unthread it from engagement with the cover-sleeve and the plunger also withdrawn until the slight protuberances 7b near its inner end engage the edge of the hole 5c through which the plunger is drawn. The 35 compression tube and loading hopper are thus empty ready to receive the charge of tobacco. By holding the device in an inclined position the tobacco can be poured into the hopper through the opening 5a whence it will fall into the compression 40 tube. As the latter fills up the device may be turned to a more nearly horizontal position and the hopper completely filled as seen in Figure 5. The cover-sleeve is then re- 45 turned to its initial position again covering the opening and confining the tobacco in the device.

The user then grasps the device just back of the cap sleeve, where the end of the hopper 50 affords a convenient grip and begins to move the plunger back and forth through the hopper and compression tube. The size of the plunger must be in such relation to the compression tube that it can be pushed 55 and pulled through the tobacco that first entered the tube without causing any binding while at the same time gradually forcing the tobacco toward the closed end of the cap-sleeve. It is desirable also to provide 60 a slight play between the plunger and the edge of hole 5c in the hopper, so that the plunger has sufficient freedom of movement.

The first few strokes of the plunger cause 65 the tobacco to pack against the ejector plate 4 and against the end of the paper wrapper

which extends beyond the compression tube, thus forcing this end of the paper against the inner wall of the cap sleeve. As the operation of the plunger continues, the tobacco is compressed in the tube, being piled 70 up ahead of the plunger. At suitable intervals as the loading progresses the compressed tobacco in the tube is bodily pushed out of the tube and with it the cap-sleeve and paper wrapping are forced along and 75 off the compression tube. This movement of the paper with the sleeve is due to the initial binding of the paper against the sleeve wall which occurred when the tobacco was first forced out of the tube and against 80 the exposed surface of the paper. Since the grip thus effected between the paper and cap-sleeve is more binding than the light friction grip between the paper and the compression tube, the paper is drawn off 85 from the latter as the cap sleeve is similarly moved by the extruded tobacco.

As is now evident, the loading goes on until all the tobacco originally placed in the hopper and compression tube is compressed 90 inside the paper wrapper. When this has been accomplished the cap-sleeve will have been forced almost completely off the compression tube and can easily be removed therefrom with the finished cigarette inside 95 it. The cigarette is now forced out of the cap sleeve by a plate ejector 4, its arms are gripped by the user's fingers and the ejector pushed along the tube, forcing the finished cigarette out ahead of it as seen in Figure 7. 100

The loading hopper 5' shown in Figures 11 and 12 is provided with an end cap 6' which frictionally grips the plunger 7 when the latter is not in use, the cap being provided with slits 6'a to give the desired grip. 105 When loading this hopper the cap 6' and plunger are entirely removed and the tobacco is poured into the thus opened end of the hopper, after which the cap and plunger are replaced, the latter being at the time fully 110 withdrawn. The loading of the paper wrapper then follows in the manner previously described. The removable cap and plunger of Figures 11 and 12 lend themselves to another use in case a prepared paper 115 wrapper is employed. These come in a flattened shape and must be made cylindrical before being filled with tobacco. The end 7a of the plunger is designedly shaped to aid in this operation and Figure 10 illustrates how the plunger may be inserted into the initially flat paper wrapper 3' and form it into a cylinder. When the end of the plunger has been pushed through the prepared wrapper it may then be inserted in the 120 end of the compression tube as shown in Figure 9 and the wrapper slipped from the plunger onto this tube. 125

The hoppers of Figures 1 and 12 are designed of such size that when the plunger 130

is withdrawn, the combined space of the hopper and compression tube will hold approximately the proper amount of tobacco needed for the finished cigarette. This quantity will of course vary depending upon the nature and granular texture of the tobacco, but the user can easily determine the amount required and thereafter be able to measure each charge with remarkable accuracy.

Figures 13 to 20 show other forms of loading hoppers, the type shown in the device of Figures 13 to 16 being an open one, while that depicted in Figures 17 to 20 is closable. The cap sleeve 21 of these devices has no extended longitudinal slots and no ejectors but has a sizable opening 2'a near one end. This enables the wrapper to be lightly gripped by the fingers when the sleeve and wrapper are initially positioned with respect to the compression tube (as shown in Fig. 4) and also enables the finished cigarette to be grasped and removed from the sleeve.

The hopper 5" of Figures 13 to 16 is made in two sections, 5'a and 5'b, one of which is secured to the compression tube 1' which extends throughout the length of this device having an opening 1'a into the hopper. The other section 5'b of the hopper is rotatably mounted on the tube so that it may be swung away from its companion section 5'a as seen in Figure 14 or swung toward it as in Figure 15. Each section has overlapping ends which form the end walls of the hopper. The latter may be proportioned so that when opened as in Figure 14 it will hold the full charge of tobacco needed for a cigarette, even with the plunger 7 within the tube. When thus filled the plunger is pulled and pushed through the tube effecting the loading of the wrapper as before described. When the operation is completed, the movable section of the hopper is swung closed thus making it compact. Preferably the construction shown in Figures 13 to 16 is entirely of metal parts, the tube and cap-sleeve being formed from metal tubing, the plunger from a simple rod and the hopper pressed from plate stock. The sections of the latter are slipped over the tube until in register with the side opening 1'a therein and then one section of the hopper is soldered to the tube. This makes a very inexpensive and yet extremely durable device.

The hopper 5'" shown in Figures 17 to 20 may also be of metal or may be of bakelite or the like. It is suitably secured at one end to the compression tube and its other end has a pivoted plate cap 6''' which can be swung to the open position seen in Figure 19 for loading. After the charge has been introduced the plate is swung closed and the plunger operated to gradually force the to-

bacco from the hopper into the paper wrapper.

The device, in whatever form made, is a highly efficient cigarette maker. The tobacco is well packed in the wrapper and yet not too tightly to prevent free drawing. The cigarettes are accurately formed and are as rigid and uniform as the best machine made product. The initial cost of the device is low and enables a smoker to make cigarettes easily and quickly when desired and with an appreciable saving.

I claim:—

1. A cigarette making device comprising a tube adapted to extend into a wrapper and having a side opening; a hopper having a section rigidly attached to said tube and having a section rotatably mounted on said tube and movable to open said hopper for introduction of tobacco; an element extending through said tube beyond said hopper and adapted to be reciprocated in said tube to effect feeding of the tobacco through the tube and into the wrapper. 80

2. A cigarette making device comprising a tube adapted to extend into a wrapper and having a side opening; a hopper in register with said side opening having a section attached to the tube and having another section movable about the tube with respect to said first section to provide a large opening for introduction of tobacco to said hopper; and an element extending through the tube and adapted to be reciprocated therein to effect feeding of the tobacco through said tube and into said wrapper. 90

3. A cigarette making device comprising a tube adapted to receive externally a paper wrapper at one end thereof and having near its other end a side opening; a sleeve adapted to fit over said wrapper and close the end thereof having openings in its wall to permit manual gripping of the wrapper; a hopper mounted on said tube in register with the side opening thereof, said hopper having a fixed section secured to the tube and having another section rotatably mounted on the tube and movable with respect to the fixed section to form a pocket converging toward the said side opening of the tube; and a plunger in the tube extending out of the hopper end thereof and adapted to be reciprocated through the tube whereby tobacco loaded into said pocket is fed through the tube into said wrapper; the wrapper and said sleeve being forced along said tube in accordance with the filling of the wrapper. 105

Signed at Attleboro, Massachusetts, county of Bristol, this 21 day of November, 1931. 110
